DRUM TYPE MAGNETIC SEPARATOR

Tage Emanuel Mortsell, deceased, late of Stockholm, Sweden, by Gunnar Ahlstrom, administrator, Gavle, Sweden, assignor to Sala Maskinfabriks Aktiebolag, Sala, Sweden, a corporation of Sweden
Continuation of abandoned application Ser. No. 500,963, Apr. 12, 1955. This application Dec. 18, 1964, Ser. No. 419,614

4 Claims. (Cl. 209—219)

This is a continuation of application Ser. No. 500,963, filed Apr. 12, 1955, now abandoned.

The present invention relates to separators for separating magnetic and non-magnetic granular materials from a mixture of such materials in a dry state. More particularly the invention relates to the separation of gangue from ores by a magnetic separator.

One object of the invention is to provide a magnetic separator of the type referred to in which, particularly with respect to certain ores, renders a high capacity and an effective separation of the gangue possible.

Another object of the invention is to provide a magnetic separator, in which the granular materials to be separated are exposed to a mutual movement under frictional engagement on the surface of a drum under the influence of the magnetic force, whereby the separation of the materials from one another is facilitated.

A further object of the invention is to provide, in a magnetic separator having a roller with closely spaced permanent magnets and a drum surrounding said roller to receive the mixture to be separated, means enabling rotation of the roller and the drum in mutually opposite directions or in the same direction or rotation only of the drum, while maintaining the roller stationary.

A still further object of the invention is to facilitate separation of non-magnetic material from the magnetic material in a mixture of such materials by aid of closely set permanent magnets with a high field strength.

The closely set permanent magnets may be made with a high field strength, and the alternating polarities and the high speed at which the material is entrained by the drum brings about a particularly rapid mutual movement of the grains (threshing) on the envelope surface of the drum, which promotes the separation of the non-magnetic grains in an effective manner. In this process it is possible to apply a comparatively thick layer of material on the drum while maintaining the separating capacity. It has been found that the separator is also capable of separating not completely crushed ore grains, so-called half-grains, which may thus be separated and re-ground to a pure ore concentrate.

The invention is further elucidated by an example of embodiment illustrated in the accompanying drawing by way of diagrammatic representation, and in which

FIGS. 1 and 2 show a dry separator constructed according to the invention in two vertical, partly-sectioned projections at right angles to each other;

FIG. 3 is a transverse vertical section of a modification, and

FIG. 4 is a diagrammatic view illustrating the close spacing of the magnets.

Mounted in the frame 1 is a hollow shaft 2 having a magnet roller 3 secured to one end thereof. The magnet roller consists of a hub 4 and of permanent magnets

2

secured therein, said magnets being arranged radially and with their out-turned ends with alternating polarities, that is to say, that a north pole is followed by a south pole, counted along the peripheral portion of the roller.

5 Mounted in the hollow shaft 2 is a shaft 6 carrying a drum 7 made from non-magnetic material splined thereto, the non-magnetic material consisting of stainless steel, for example. The envelope surface of the drum extends with a small clearance round the magnet roller 4 along the peripheral portion of the latter.

By means of a driving contrivance, shown as a pulley 8 on the shaft 6, a high rotational speed may be imparted to the drum 7. The magnet roller 3 may be driven in the same direction but at a lower speed, and for this purpose

15 there is provided a gearing consisting, for example, of a gear wheel 9 secured to the pulley 8 and meshing with a smaller gear wheel 10 secured on an intermediate shaft 11, which also has secured thereon a still smaller gear wheel 12 in engagement with a larger gear wheel 14 secured to the shaft 2 of the magnet roller. The intermediate shaft is rotatably but non-displaceably mounted on a slide rod 15 pertaining to an operating contrivance carried by the frame, by means of which contrivance the wheels 10, 12 of the intermediate shaft may be brought into or out of engagement with the gear wheels 9 and 14.

20 At 16 is shown a device for the supply of a mixture of magnetic and non-magnetic granular material, and 17 denotes a collection contrivance in the form of a casing for the separated non-magnetic material; 18 designates 25 a collecting device provided with a funnel and a container for the magnetic material. A rotating prong roller 19 may be provided to remove the magnetic material from the drum in the known manner, after the non-magnetic material has been separated.

30 The mode of operation of the magnetic separator may be generally stated as follows:

The mixture of magnetic and non-magnetic pulverulent material to be separated is supplied through the device 16 and falls down onto the envelope surface of the drum

40 7 in a relatively thick layer. The magnetic material is retained by the magnets, and accordingly as the drum moves relatively to the magnets, the grains of the material are brought into movement relatively to each other so as to rub against one another, the non-magnetic material in the layer then travelling outwardly to be hurled out from the drum through the influence of the centrifugal force, this material then being collected in the collecting contrivance 17. The magnetic material is entrained to the removing roller 19, where it is removed from the drum 45 and collected in the known manner.

50 With respect to the high peripheral speed of the drum 7 required by the centrifugal separation, it will be preferable, at least for certain kinds of materials, to cause the magnet roller to rotate in the same direction as the drum 55 but at a lower speed than the latter, in which case the gearing 9 to 14 is thrown in, so that the movement of the magnet roller is obtained from the pulley 8 over the gear wheels 9, 10, 11 and 14 and the shafts 11 and 2.

The magnet roller may also be stationary, and in such 60 case the intermediate shaft 11 is displaced to the right in FIG. 1 by means of the operating contrivance 15, so that the gear wheels 10 and 12 are out of engagement with the gear wheels 9 and 14.

With a stationary magnet roller or frame, the prong 65 roller might optionally be omitted, the magnet roller then

being without magnets along a portion of its circumference. The magnetic grains will then leave the drum, as soon as they have been brought by the latter out of the magnetic field, that is to say, to the region of the gap between the magnets. This modification is illustrated in FIG. 3, in which 3' designates the stationary magnet frame carried by a hub 4' and carrying permanent magnets 5' with alternating polarity mounted along a portion of the periphery, a gap 20 having no magnets being provided over a section in advance of the topmost point of the rotary drum 7 where the material to be separated is supplied through the feeding device 16. The material is delivered to the device 16 by a hopper 16'. A collecting housing 21 comprises three compartments, one 22 for the non-magnetic material, the second 23 for an intermediate product and the third 24 for magnetic material of the highest concentration (purity). The attracted material which has not been discharged from the rotating drum 7 by centrifugal action will leave the latter substantially at the point 25, where the attraction by the magnets ceases. The material in the compartments drops through bottom outlets 26, 27 and 28, respectively. A baffle plate 29 pivoted at 30 between the compartments 22 and 23, and a similar baffle plate 31 pivoted at 32 between the compartments 23 and 24 may be set in various positions as indicated by the arrows 33 to vary the ratio between the portions of the material which is discharged from the drum 7 and collected in the compartments 22, 23 and 24.

An important feature of this invention resides in the close spacing of the magnets, or more specifically, the pitch of the magnets counted on the periphery of an imaginary cylinder co-axial with the surrounding drum or with the center of the support for the magnets. The pitch in this connection is equal to the distance between the centers of the out-turned end surfaces of two arbitrary adjacent magnets and is illustrated in FIG. 4. In this view of the drawings, p indicates the pitch, m indicates the magnets and c represents an imaginary cylinder contacting with the out-turned ends of the magnets. A large number of pole alterations are of importance for a complete separation of the fine grained materials. That is, the materials being separated should be moved by the drum past as many poles as possible. The particles of the material being under separation are indicated on the external surface of the drum d which rotates around the magnet system. The particles form chains in the magnetic field and opposite to the space between adjacent magnets the particles chains protrude as indicated at e . It has been found that a great number of these protruding chain groups are of importance for the separation since the material moves and turns as the drum surfaces passes the magnets and this facilitates the discharge of the non-magnetic grains.

In the two examples herein mentioned, the maximum pitch indicated is 45 millimeters. In the first example reference is made to a separator having a diameter of 400 millimeters and 48 poles as well as a gap corresponding to 6 magnets or 12 poles. The total number of poles is thus 60, and a pitch diameter of a 400 millimeter cylinder is:

$$p = \frac{\pi \times 400}{60} = 21$$

In the further example:

$$p = \frac{\pi \times 400}{28} = 45$$

The maximum pitch indicated in the above examples is thus 45 and this arrangement is important to the best functioning of the apparatus.

The invention is not restricted to the embodiments shown and described, this embodiment only referring to an example having for its object to facilitate an understanding of the invention. If necessary, the separation

of fine powder may be facilitated by an air jet directed against the drum.

Having thus described an embodiment of the invention, it is obvious that the same is not to be restricted thereto, but is broad enough to cover all structures coming within the scope of the annexed claims.

What is claimed is:

1. A magnetic separator for mixtures of magnetic and non-magnetic dry granular materials comprising, a stationary magnet support, a plurality of permanent magnets mounted in close proximity to one another on said support with their out-turned ends located in an imaginary cylinder surface, the pitch of the magnet ends in said surface consisting of the peripheral distance between the centers of the magnets, being a maximum of 45 millimeters, the out-turned end of one magnet having different polarity as compared with the out-turned ends of adjacent magnets, a drum peripherally surrounding the magnets, said drum being co-axial with said imaginary cylinder surface, means for supplying the mixture to the top of the drum and at a point located above the magnets, and means for rotating the drum at a peripheral speed sufficient to remove the non-magnetic material from the drum through the action of the centrifugal force.

2. A magnetic separator for separating magnetic material from a mixture of magnetic and non-magnetic dry granular material comprising, a stationary magnet support, a plurality of permanent magnets mounted in close proximity to one another over a substantially cylindrical

part of said support in substantially radial positions, said cylindrical part being at least 180 degrees and beginning substantially at the top of the support, the outer ends of the magnets having their end surfaces located on an imaginary cylinder surface and being alternately of different polarity, the pitch of the pole surfaces having a maximum magnitude of 45 millimeters, a drum co-axial with said cylinder surface and peripherally surrounding the magnets, means for supplying the mixture to be separated to the periphery of the drum at the top of the

same, and means for rotating the drum at a peripheral speed sufficient to cause release of the non-magnetic material from the drum through the action of the centrifugal force while permitting the magnetic material to be retained on the drum for subsequent removal therefrom.

3. A magnetic separator for separating magnetic material from a mixture of magnetic and non-magnetic material comprising, a stationary magnet support, a plurality of permanent magnets mounted in close proximity to one another over a cylindrical part only of the circumference

50 of the support in substantially radial positions, the outer ends of adjacent magnets having different polarities and being located in an imaginary cylinder surface, a drum peripherally surrounding said magnets, the pitch of the magnets ends in said surface being a maximum of 45 millimeters, means for supplying a mixture to be separated, said means supplying said mixture to the periphery of the drum at a point located substantially at the top of the drum and at which point the drum begins its travel downwardly, means for rotating the drum at a peripheral speed sufficient to cause release of the non-magnetic material from the drum through the action of the centrifugal force while permitting the magnetic material to adhere to the drum, the support having a gap

60 between its magnets beginning substantially at the top of the inside of the drum and ending at a distance therefrom corresponding to the total pitch of at least five magnets.

4. A magnetic separator as provided for in claim 3, wherein the support and drum are contained in a housing having a lower portion arranged below the support and drum, said lower portion being divided into a plurality of separate outlets past which the drum is successively rotated, one of the outlets receiving non-magnetic material from the drum, and a second outlet receiving

magnetic material, the latter outlet being so positioned relative to the gap between the magnets that by movement of the magnetic material by the drum out of the magnetic field, and which magnetic field is interrupted by the gap, the magnetic material will fall from the drum and be received in the last-mentioned outlet.
